UNITED STATES PATENT OFFICE.

SAMUEL MARCOTTE, OF HUBBELL, MICHIGAN.

TAMPING MACHINE.

Application filed September 17, 1921. Serial No. 501,346.

To all whom it may concern:

Be it known that I, SAMUEL MARCOTTE, citizen of the United States; residing at Hubbell, in the county of Houghton and 5 State of Michigan, have invented certain new and useful Improvements in Tamping Machines, of which the following is a specification.

This invention relates to an improved concrete tamping machine, being particularly designed for use in tamping concrete blocks, and seeks to provide a machine of simple and sturdy construction whereby the wet material may be quickly and compactly 15 tamped in a mold to form a homogeneous and well-knitted block.

A further object of the invention is to provide a machine which will be power operated and wherein the operation of the 20 tampers employed may be readily controlled.

And the invention has as a still further object to provide a machine wherein the tampers may be rendered inactive without 25 cutting off the motive power driving the machine.

Other and incidental objects will appear hereinafter.

In the drawings:

30 Figure 1 is a front elevation of my improved tamping machine,

Figure 2 is an edge elevation, parts being broken away and shown in section,

35 Figure 3 is a perspective view of one of the tamper lifting members of the device,

Figure 4 is a detail perspective view showing one of the tappets employed,

40 Figure 5 is a fragmentary elevation showing one of the finger holders of the device, and

Figure 6 is a transverse sectional view on the line 6—6 of Figure 5, looking in the direction of the arrows.

In carrying the invention into effect, I 45 employ a supporting frame comprising spaced horizontal beams 10 to which are connected parallel uprights 11 and extending transversely between said uprights are vertically spaced cross bars 12 bolted or 50 otherwise secured to the uprights. Slidably supported by the cross bars 12 is a plurality of tampers. Each of these tampers includes a pair of spaced parallel rods 13 which are 55 freely received through the bars 12 and mounted upon the lower ends of said rods

is a plate or foot 14. Fixed to the intermediate portions of the rods is a tappet 15 provided at its inner end with a transversely disposed head 16 receiving the rods therethrough, the tappet being held fixed upon 60 the rods by suitable set screws threaded through the head to engage the rods. The tappet lies medially between the rods projecting forwardly therefrom and freely surrounding the rods to rest against the head of 65 the tappet is a pair of cushioning springs 17. Threaded upon the rods at their upper ends are nuts 18 and freely surrounding the rods to bear between these nuts and the uppermost of the cross bars 12 is a second pair 70 of cushioning springs 19. Secured to the lower end portions of the uprights 11 at their rear edges are alined bearing brackets 20 and journaled upon these brackets is a power shaft 21 to one end of which is 75 fixed a collar 22 coacting with one of the brackets while upon the opposite end of said shaft is fixed a drive pulley 22 coacting with the other of the brackets. Any approved source of motive power may be 80 employed for turning the pulley and rotating the power shaft. Fixed upon the power shaft is a plurality of elevating members for the tampers, one for each tamper. As shown in detail in Figure 3, each of these elevating members includes a hub 23 keyed or otherwise secured to the shaft and mounted upon the hub is a pair of oppositely directed 85 spring arms 24. At their inner ends, these arms are bowed to provide mating clamping members 25 encircling the hub and extending through the arms at opposite sides of the hub are bolts 26 rigidly securing the arms together as well as also binding the arms about the hub. At their outer end 90 portions the arms are curved laterally in opposite directions and at their outer terminals are notched to accommodate rollers 27 carried by pins 28 extending through bearings 29 at the outer terminals of the arms. 100 As brought out in Figures 1 and 2, the elevating members are so arranged upon the power shaft that when said shaft is rotated the arms of said members will pass between the rods 13 of the tampers to coact with the 105 tappets 15, the rollers 27 being provided, of course, to engage the tappets.

Mounted upon the uprights 11 near their lower ends are alined bearing brackets 30 secured against the forward edges of said up- 110

rights and journaled upon said brackets is a shaft 31 having collars thereon to coact with the brackets holding the shaft against longitudinal movement. Secured to one end of the shaft is a control lever 32 and fixed upon the shaft at longitudinally spaced points therealong are upstanding channeled finger holders 33. Pivoted at their lower ends in said holders are, as particularly shown in Figure 5, vertically disposed fingers 34 and secured to the outer side walls of said holders to coact at their free ends with said fingers are longitudinally curved finger springs 35 yieldably holding the fingers to abut the opposite side walls of the holders. As will be observed upon reference to Figure 1, the fingers 34 are each arranged opposite one of the rods of the tampers respectively and at their upper ends are adapted to coact with the heads 16 of the tappets 15.

In practical operation, the power shaft is rotated for turning the elevating members so that the rollers 27 upon the arms 24 of said members will be swung to coact with the tappets 15 for successively elevating the tampers, it being observed in this connection that the elevating members are staggered with respect to each other upon the power shaft. As the elevating members revolve, the tampers will, as will be readily understood, be successively lifted each to the top of its stroke and then released to drop by gravity for accomplishing the tamping operation, each of the tampers being thus elevated and released twice for each revolution of the power shaft. The cushioning springs 17 will, when the tampers are elevated, coact with the uppermost of the cross bars 12 for cushioning the tampers at the limit of their upward throw while the springs 19 will coact between the nuts 18 of the tampers and said bar for cushioning the tampers at the limit of their downward throw. In order to thus permit the operation of the tampers, the free end of the control lever 32 is lifted for rocking the shaft 31 and swinging the fingers 34 outwardly so as to dispose the upper ends of said fingers out of the path of travel of the heads 16 of the tappets. On the other hand, when it is desired to stop the tampers the free end of the lever 32 is shifted downwardly for swinging the upper ends of the fingers inwardly so that as each of the tampers is elevated to the limit of its upward movement the stop finger therefor will engage beneath the head of the tappet of said tamper. Accordingly, the several fingers will hold

all of the tampers elevated, the springs 35 being provided so that after the upper ends 60 of the fingers have been swung inwardly to coact with the tappets, the heads of the tappets may ride upwardly beneath said fingers swinging the fingers outwardly against the tension of said springs. Accordingly, when 65 the tampers reach the upper limit of their movement, the springs will serve to rock the fingers and snap the upper ends thereof under the heads 16 of the tappets. The reciprocating movement of the tampers may thus 70 be readily controlled without stopping the power shaft.

Having thus described the invention, what is claimed as new is:

1. A tamping machine including a reciprocating tamper, a tappet carried thereby, a power shaft, and an elevating member carried by said shaft and having spring arms to selectively coact with the tappet for lifting the tamper. 75

2. A tamping machine including a reciprocating tamper, a tappet carried thereby, means to coact with the tappet for lifting the tamper, a rock shaft, a channel shaped finger holder fixed thereto, a finger pivoted 85 within the channel of said holder and shiftable by the shaft to engage beneath said tappet for holding the tamper elevated, and a spring fixed to one wall of said channel normally holding said finger to engage the opposite wall thereof whereby the tappet may ride upwardly beneath the finger when said finger is swung to position for engagement with the tappet. 90

3. In a tamping machine, the combination 95 of a reciprocating tamper, and rotatable resilient means for lifting and releasing the tamper.

4. In a tamping machine, the combination 100 of a reciprocating tamper, a power shaft, and a pair of oppositely directed oppositely curved spring arms fixed to said shaft and operatively engageable with the tamper selectively for lifting the tamper.

5. In a tamping machine, the combination 105 of a reciprocating tamper, a power shaft, a hub fixed to said shaft, oppositely directed spring arms provided at their inner ends with bowed portions fitting the hub in mating relation, and means connecting the arms 110 clamping the bowed portions thereof about the hub, the arms being operatively engageable with the tamper selectively for lifting the tamper.

In testimony whereof I affix my signature. 115
SAMUEL MARCOTTE. [L.S.]
